RAILWAY SIGNALING SYSTEM

Samuel G. Raber, Youngstown, Ohio, assignor to
 Associated Electric Laboratories, Inc., Chicago,
 Ill., a corporation of Delaware

Application June 9, 1939, Serial No. 278,320

5 Claims. (Cl. 246—5)

The present invention relates to railway signaling systems and more particularly to telephone train dispatching systems.

A telephone train dispatching system conventionally comprises a number of waystations located at different points along a system of railway track, a dispatcher station, a telephone line interconnecting the various stations and telephone equipment at each of the stations operationally associated with the telephone line. Also, signal devices disposed along the system of railway track are individually controlled by the operators at the various waystations. In a dispatching system of the type described, the operators at the various waystations inform the dispatcher at the dispatcher station of the movements of the trains in the associated portions of the system of railway track and operate the signal devices disposed along the system of railway track in accordance with the instructions of the dispatcher.

While a dispatching system of the type described is reasonably satisfactory in operation, it necessitates an operator at each waystation and requires the dispatcher to depend upon the operators at the waystations to report the movements of the trains in the system of railway track and to operate the signal devices associated with the system of railway track in accordance with his instructions.

Accordingly, it is an object of the present invention to provide an improved telephone train dispatching system, including a dispatcher station and a number of unattended waystations, which is so connected and arranged that the movements of trains in an associated system of railway track and the operations of signal devices associated therewith may be supervised at and controlled from the dispatcher station over the telephone line.

Another object of the invention is to provide an improved railway signaling system, including a system of railway track and a dispatcher station provided with a telephone line, which is so connected and arranged that the movements of trains in the system of railway track are automatically reported over the telephone line to the dispatcher station, that signal devices associated with the system of railway track are governable from the dispatcher station over the telephone line, and that the operations of the signal devices are automatically reported over the telephone line to the dispatcher station for purposes of verification.

It is another object of the invention to pro-

vide, in a signaling system of the type described, improved and exceedingly simple apparatus for transmitting control impulses and ringing current over an associated telephone line.

5 It is a further object of the invention to provide, in a signaling system of the type described, improved and exceedingly simple apparatus governable over an associated telephone line for controlling the operations of an associated signal device.

The features of the present invention are illustrated as being incorporated in a railway signaling system including a system of railway track, a dispatcher station and a number of waystations, at least some of the waystations being unattended, and a telephone line interconnecting the various stations. Telephone equipment is provided at the dispatcher station and at each of the attended waystations; and a number of signal devices are located along the system of railway track and individually associated with certain of the waystations.

In accordance with one feature of the invention, each of the unattended waystations 25 comprises first and second apparatus, each of which is operative to transmit a signal over the associated telephone line; first and second start means respectively operative to initiate the operations of the first and second apparatus; first 30 and second stop means respectively operative to arrest the operations of the first and second apparatus; means including a relay network for selectively controlling the operations of the signal device located along the system of railway track and associated with the waystation; and a control network including a selector switch. The control network is so connected and arranged that, when a train passes over a fixed point along the system of railway track 35 associated with the waystation, the first start means is operated and the first apparatus is controlled to transmit a signal over the telephone line indicative of the location of the fixed point and of the direction of movement of the train. 40 Predetermined operations of the selector switch selectively control the relay network and operate the second start means, thereby to cause the signal device to present a given signal. The second apparatus is controlled by the operation of 45 the signal device to present a given signal to transmit a signal over the telephone line indicative of the given signal. Different predetermined operations of the selector switch selectively operate the first and second stop means. 50 Finally, means is provided at the dispatcher sta-

tion for selectively governing over the telephone line the operations of the selector switch. Preferably, the fixed point located along the system of railway track associated with the waystation precedes the associated signal device in order to afford the dispatcher at the dispatcher station ample opportunity to control the selector switch, thereby to effect an operation of the signal device to present a different signal prior to the arrival of the train at the signal device.

In accordance with another feature of the invention, the apparatus provided at the dispatcher station comprises corresponding impulse devices, signals and control relays, an operating circuit for each of the control relays including the corresponding impulse device, a holding circuit for each of the control relays, and an operating circuit for each of the signals. These circuits are so connected and arranged that the holding circuit of one of the control relays and the operating circuit of the corresponding one signal are normally completed as determined by the last operated and corresponding one of the impulse devices. When another of the impulse devices is operated the operating circuit of the corresponding other control relay is completed, thereby to cause the other control relay to operate. Upon operating, the other control relay interrupts the holding circuit of the one control relay and the operating circuit of the corresponding one signal. The operation of the other control relay and the restoration of the one control relay completes the holding circuit of the other control relay and the operating circuit of the corresponding other signal. Further, there is provided at the dispatcher station an impulse circuit, means controlled by the operation of the other control relay prior to the restoration of the one control relay for operatively associating the impulse circuit with the telephone line at the dispatcher station, and means governed by the operation of the other impulse device for controlling the impulse circuit, whereby impulses individual to the other impulse device are transmitted over the telephone line. Finally, the apparatus at the dispatcher station comprises a ring circuit, means controlled after the operation of the other impulse device for operatively associating the ring circuit with the telephone line, whereby ringing current is transmitted over the telephone line, and means at the operator position for disassociating the ring circuit from the telephone line.

In accordance with a further feature of the invention, the relay network at each of the unattended waystations comprises a number of signal relays individually corresponding to the different signals which the associated signal device is operative to present, and an operating circuit and a holding circuit for each of the signal relays. These circuits are so connected and arranged that the holding circuit of one of the signal relays is normally completed as determined by the last operated one of the signal relays, thereby to cause the signal device to operate to present a signal corresponding to the one operated signal relay. When the selector switch is operative to complete the operating circuit of another of the signal relays, the other signal relays operate to interrupt the holding circuit of the one signal relay in order to cause the one signal relay to restore. The operation of the other signal relay and the restoration of the one signal relay is effective to complete the holding circuit of the other signal relay and to

cause the signal device to present a signal corresponding to the other signal relay.

Further features of the invention pertain to the particular arrangement of the circuit elements thereof, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings, in which Figures 1 to 4, inclusive, taken together, illustrate diagrammatically the details of a railway signaling system having incorporated therein the features of the present invention.

Referring now more particularly to Figs. 1 to 4, inclusive, of the drawings, the railway signaling system there illustrated comprises a first stretch of main railway track 50, along which traffic normally moves from the right toward the left, or in a westbound direction, as indicated by the arrows; and a second stretch of main railway track 60, along which traffic normally moves from the left toward the right, or in an eastbound direction, as indicated by the arrows. Furthermore, each of the stretches of main railway track may communicate with one or more stretches of side railway track and one or more stretches of branch railway track. For example, the stretch of main railway track 50 communicates with the stretch of side railway track 70; while the stretch of main railway track 60 communicates with the stretch of side railway track 80 and the stretch of branch railway track 90.

An automatic block signaling system of conventional connection and arrangement is associated with each of the main railway tracks 50 and 60. More particularly, the main railway track 50 comprises track rails 51 and 52 which are divided by suitable insulating joints 53 to form a plurality of track sections 54, 55, 56, 57, 58, etc.; while the main railway track 60 comprises track rails 61 and 62 which are divided by suitable insulating joints 63 to form a plurality of track sections 64, 65, 66, 67, etc. Each of the track sections has a battery and a track relay individually associated therewith, the track relays individually associated with the track sections 55, 64, 65, 66, 67, etc., being respectively indicated at R210, R195, R110, R105, R100, etc. Also, visual signals of the semaphore type are disposed along the right of way of each of the main railway tracks 50 and 60 and are connected and arranged to display clear, caution and stop indications as controlled by the traffic conditions in the two track sections immediately succeeding a reference track section in accordance with conventional practice. For example, the signals E, G and H are disposed along the right of way of the main railway track 50 and are respectively positioned adjacent the beginnings of the track sections 57, 56 and 55; while the signals C and A are disposed along the right of way of the main railway track 60 and are respectively positioned adjacent the beginnings of the track sections 65 and 64.

Also, automatic block signaling systems may be associated with each of the branch railway tracks and with each of the side railway tracks; however, it is not ordinarily necessary to associ-

ate automatic block signaling systems with the side railway tracks as the side railway tracks are usually relatively short. Furthermore, visual signals of the semaphore type are disposed along the right of way of each of the main railway tracks 59 and 60 in proximity to the side railway tracks communicating therewith, in order to signal a train proceeding along the main railway track to take the associated side railway track in a manner more fully described hereinafter. For example, the signal F is disposed along the right of way of the main railway track 59 and positioned adjacent the beginning of the track section 57 which communicates with the side railway track 79; while the signal B is disposed along the right of way of the main railway track 60 and positioned adjacent the beginning of the track section 64 which communicates with the side railway track 80. Finally, visual signals of the semaphore type are disposed along the right of way of each of the branch railway tracks in proximity to the main railway track communicating therewith, in order to signal a train proceeding along the branch railway track to take the communicating main railway track in a manner more fully described hereinafter. For example, the signal D is disposed along the right of way of the branch railway track 90 and positioned adjacent the beginning of the track section 67 of the main railway track 60 communicating with the branch railway track 90.

The signaling system also comprises a dispatcher station 30, a plurality of waystations 20, 21, etc., and a telephone line 40 extending therebetween. It is noted that the waystation 20 is associated with the main railway track 60 adjacent the track sections 64, 65, 66 and 67 thereof; while the waystation 21 is associated with the main railway track 59 adjacent the track sections 54, 55, 56 and 57 thereof.

Each of the waystations 20 and 21 comprises order signaling apparatus, answer-back apparatus and a control network for governing the operations of the order signaling apparatus and the answer-back apparatus. For example, the waystation 20 comprises, as best shown in Fig. 1 and on the left-hand side of Fig. 2, order signaling apparatus 201 and answer-back apparatus 203. The order signaling apparatus 201 at the waystation 20 is primarily under the joint control of the track sections of the main railway track 60 associated with the waystation 20 and the telephone line 40; while the answer-back apparatus 203 at the waystation 20 is primarily under the joint control of the signal B disposed adjacent the beginning of the track section 64 of the main railway track 60 and the telephone line 40. More specifically, the control network for the order signaling apparatus 201 and the answer-back apparatus 203 comprises the track relays R100, R105, R110 and R195 respectively associated with the track sections 67, 66, 65 and 64; and a number of control relays R115, R120, R130, R135, R149, R160, R170 and R175. Further, this control network comprises a group of signaling relays, including a siding relay R145, a clear relay R150 and a stop relay R155; a selector switch 185; a mechanical switch S180 directly controlled by the position of the signal B; and suitable control circuits interconnecting the elements of the control network previously mentioned. Specifically, it is noted that the lines 530, 520, 510 and 500 respectively extend to the signals D, C, B and A, thereby to control the operated positions of the respective signals. 75

Similarly, the waystation 21 comprises, as best shown in Fig. 4 and on the right-hand side of Fig. 2, order signaling apparatus 400 and answer-back apparatus 470. The order signaling apparatus 400 at the waystation 21 is primarily under the joint control of the track section 55 of the main railway track 59 associated with the waystation 21 and the telephone line 40; while the answer-back apparatus 470 at the waystation 21 is primarily under the joint control of the signal F disposed adjacent the beginning of the track section 57 of the main railway track 59 and the telephone line 40. More specifically, the control network for the order signaling apparatus 400 and the answer-back apparatus 470 comprises the track relay R210 associated with the track section 55; and a number of control relays R215, R220, R245 and R250. Further, this control network comprises a group of signaling relays, including a siding relay R230, a clear relay R235 and a stop relay R240; a selector switch 260; a mechanical switch S225 directly controlled by the position of the signal F; and suitable control circuits interconnecting the elements of the control network previously mentioned. Specifically, it is noted that the line 295 extends to the signal F, thereby to control the operated positions of the signal.

Preferably, the order signaling apparatus at the various waystations are connected and arranged in a manner substantially identical to the order signaling apparatus 400 at the waystation 21. As best shown in Fig. 4, the order signaling apparatus 400 at the waystation 21 comprises a rotary switch 401, including four rotary wipers 402, 403, 404 and 405 and four contact banks 406, 407, 408 and 409 respectively associated therewith; and a motor magnet M410 for driving the wipers noted. It is noted that each of the wipers 402, 403, 404 and 405 is of the bridging type, such that the wiper engages the succeeding contact in the associated contact bank before it disengages the contact in the associated contact bank which it engages at any given time. Further, the order signaling apparatus 400 comprises two start relays R460 and R465; a step relay R415; an impulse relay R420; a stop relay R425; a number of control relays R430, R440, R450 and R455; and a control network for the elements mentioned. Finally, the order signaling apparatus 400 includes a repeater 436 operatively associated with the telephone line 40.

Preferably, the answer-back apparatus at the various waystations are connected and arranged in a manner substantially identical to the answer-back apparatus 470 at the waystation 21. As best shown in Fig. 4, the answer-back apparatus 470 at the waystation 21 comprises a rotary switch 471, including three rotary wipers 472, 473 and 474 and three contact banks 475, 476 and 477 respectively associated therewith; and a motor magnet M490 for driving the wipers noted. It is noted that each of the wipers 472, 473 and 474 is of the bridging type, such that the wiper engages the succeeding contact in the associated contact bank before it disengages the contact in the associated contact bank which it engages at any given time. Further, the answer-back apparatus 470 comprises a step relay R485, an impulse relay R480 and a control network for the elements mentioned. Finally, the answer-back apparatus 470 includes a repeater 462 operatively associated with the telephone line 40.

Preferably, the selector switches 185 and 260 respectively provided at the waystations 20 and

21 are identical, each of these switches being of a well-known type of construction and of the general character of that shown in Joseph C. Field Patent No. 1,200,095, granted October 3, 1916. Preferably, each of the control relays R115, R120, R135, R160 and R175, arranged in the control network at the waystation 20, and the control relay R250, arranged in the control network at the waystation 21, is of a well-known polarized type, the relay including two sets of contact springs. The relay is so constructed and arranged that when the winding thereof is de-energized, both of the sets of contact springs occupy their restored positions; when the winding of the relay is energized with current of one polarity, one of the contact spring sets occupies its operated position and the other of the contact spring sets occupies its restored position; and when the winding of the relay is energized with current of the opposite polarity, both of the contact spring sets occupy their operated positions.

The dispatcher station 30 comprises, as best shown in Fig. 3, a plurality of groups of impulsing keys and a plurality of corresponding groups of signaling relays, each group of impulsing keys and the corresponding group of signaling relays corresponding respectively to one of the waystations. Each group of impulsing keys comprises a clear key, a siding key and a stop key; and the corresponding group of signaling relays comprises a clear relay, a siding relay and a stop relay. For example, the group of impulsing keys, including the clear key K315, the siding key K310 and the stop key K305, and the corresponding group of signaling relays, including the clear relay R355, the siding relay R350 and the stop relay R345, correspond to the waystation 20 and are connected and arranged to control by way of the telephone line 40 the signals A and B positioned at the beginning of the track section 64 of the main railway track 60 associated with the waystation 20. Similarly, the group of impulsing keys, including the clear key K330, the siding key K325 and the stop key K320, and the corresponding group of signaling relays, including the clear relay R370, the siding relay R365 and the stop relay R360, correspond to the waystation 21 and are connected and arranged to control by way of the telephone line 40 the signal F positioned at the beginning of the track section 57 of the main railway track 50 associated with the waystation 21.

Also, a group of impulsing keys is provided at the dispatcher station 30 for releasing the order signaling apparatus at the various waystations in a manner more fully described hereinafter. For example, the impulsing keys K335 and K340 are operative to release the order signaling apparatus at the waystations 20 and 21, respectively. Furthermore, a key K395 is provided at the dispatcher station 30 for releasing the selector switches at the various waystations in a manner more fully described hereinafter. Also, there are provided at the dispatcher station 30 a start relay R390, an impulse relay R375, two control relays R380 and R385, and a control network for interconnecting the previously mentioned elements of the equipment provided at the dispatcher station 30 with the telephone line 40. The last-mentioned control network comprises a repeater 302 and a coupling unit 301 including a ring circuit for operatively interconnecting the telephone line 40, the telephone instrument 300 provided at the dispatcher station 30 and an impulsing circuit controlled by the impulse relay

R375. Finally, it is noted that a number of lamps L309, L314, L319, L324, L329 and L334 are provided at the dispatcher station 30 which are operatively associated with the various signaling relays thereat in order to indicate the operated positions of the signals disposed along the right of way of the main railway tracks and associated with the various waystations in a manner more fully described hereinafter.

10 The connection and arrangement of the signaling system will best be understood from a consideration of the description of the operation thereof incident to the movement of traffic along the various railway tracks appearing hereinafter.

15 Assuming that the track section 55 of the main railway track 50 and the track sections 64, 65, 66 and 67 of the main railway track 60 are unoccupied and that the dispatcher at the dispatcher station 30 has last operated the clear impulsing keys K315 and K330, thereby to cause the signals F and A respectively associated with the main railway tracks 50 and 60 to display clear indications, in a manner more fully described hereinafter, considerable apparatus in the waystations 20 and 21 and in the dispatcher station 30 occupy operated positions. For example, at this time, in the dispatcher station 30 the clear relays R355 and R370 occupy operated positions. More specifically, the clear relay R355 is retained in its operated position due to a completed holding circuit for energizing the winding thereof, this circuit extending from the positive terminal of battery by way of RA346 and the back contact associated therewith, RA352 and the back contact associated therewith, RA358, and the winding of R355 to the negative terminal of battery. Also, the lamp L319 associated with the clear relay R355 and the clear impulsing key K315 is illuminated by way of a circuit extending from the positive terminal of battery by way of RA346 and the back contact associated therewith, RA352 and the back contact associated therewith, RA358, and the lamp L319 to the negative terminal of battery. The clear relay R370 is retained in its operated position due to a completed holding circuit for energizing the winding thereof, this circuit extending from the positive terminal of battery by way of RA361 and the back contact associated therewith, RA367 and the back contact associated therewith, RA373, and the winding of R370 to the negative terminal of battery. Also, the lamp L334 associated with the clear relay R370 and the clear impulsing key K330 is illuminated by way of a circuit extending from the positive terminal of battery by way of RA361 and the back contact associated therewith, RA367 and the back contact associated therewith, RA373, and the lamp L334 to the negative terminal of battery.

20 Furthermore, at the waystation 20, the track relays R100, R105, R195 and R110 respectively associated with the track sections 67, 66, 64 and 65 of the main railway track 60, occupy operated positions, these relays being energized by way of obvious circuits including the windings thereof and the batteries provided in the respective track sections. Accordingly, at this time, a circuit is completed for energizing in series the polarized relay R115 and the control relay R130. The last-mentioned circuit extends from the positive terminal of battery by way of the winding of R130, RA111 and the front contact associated therewith, C560, RA106, RA101, the winding of R115, RA102, RA107, C561 and RA112 and the front contact associated therewith to the negative terminal of battery.

minal of battery. It is noted that the polarized relay R115 occupies its fully operated position, thereby to retain completed, at the contacts RA116, RA117 and RA118, obvious paths for applying negative battery potential to the conductor C531 of the line 530 and for applying positive battery potential to the conductors C532 and C533 of the line 530. When negative battery potential is applied to the conductor C531 and positive battery potential is applied to the conductors C532 and C533 of the line 530 extending to the signal D associated with the branch railway track 90, the signal D is operated to display a clear indication in a well known manner. The operated track relay R110 associated with the track section 65 and the operated track relay R195 associated with the track section 64, retain completed a circuit for energizing the winding of the polarized relay R120, this circuit extending from the positive terminal of battery by way of the switch spring 199 and the front contact associated therewith, C565, RA114, the winding of R120, RA113, C564 and the switch spring 197 and the front contact associated therewith to the negative terminal of battery. It is noted that the switch springs 196 and 197 are included in the battery reversing switch S195 which is governed by the track relay R195 associated with the track section 64, in a manner similar to the switch springs RA111 and RA112 controlled by the track relay R119. Accordingly, the polarized relay R120 occupies its fully operated position, thereby to retain completed, at RA123, RA124, and RA125, obvious paths for applying negative battery potential to the conductor C521 of the line 520 and for applying positive battery potential to the conductors C522 and C523 of the line 520. When negative battery potential is applied to the conductor C521 and positive battery potential is applied to the conductors C522 and C523 of the line 520 extending to the signal C associated with the main railway track 60, the signal C is operated to display a clear indication in a well known manner.

The operated control relay R130, the operated track relay R105, and the operated polarized relay R120 retain completed a circuit for energizing the winding of the polarized relay R135, this circuit extending from the positive terminal of battery by way of RA131 and the front contact associated therewith, C562, RA108, RA122, the winding of R135, RA121, RA109, C563 and RA132 and the front contact associated therewith to the negative terminal of battery. Accordingly, the polarized relay R135 occupies its fully operated position, thereby to retain completed, at RA136 and the front contact associated therewith and at RA137, a circuit for energizing the winding of the control relay R140. The last-mentioned circuit extends from the positive terminal of battery by way of RA136 and the front contact associated therewith, RA137 and the winding of R140 to the negative terminal of battery. Thus, the control relay R140 occupies its operated position and retains interrupted, at RA141 and at RA142, points in paths, traced hereinafter, for applying positive battery potential to the conductors C550 and C551, respectively, extending to the order signaling apparatus 201.

Also, the clear relay R150 occupies its operated position due to the fact that the holding circuit thereof is completed, this circuit extending from the positive terminal of battery by way of the resistor 198, RA149 and the back contact associated therewith, RA153 and the

front contact associated therewith, RA151, C518 and the winding of R150 to the negative terminal of battery. The operated clear relay R150 and the restored siding relay R145 retain completed a circuit for energizing the winding of the polarized relay R160, this circuit extending from the positive terminal of battery by way of RA147 and the back contact associated therewith, RA152 and the front contact associated therewith, C567, 10 the winding of R160, C566, RA151 and the front contact associated therewith, and RA146 and the back contact associated therewith to the negative terminal of battery. Accordingly, the polarized relay R160 occupies its fully operated position, thereby to retain completed, at RA161, RA162, RA165 and RA166, a circuit for energizing the winding of the polarized relay R175. The last-mentioned circuit includes the line 540 and extends from one conductor thereof by way of RA161, RA166, the winding of R175, RA165 and RA162 to the other conductor thereof. The conductors mentioned of the line 540 extend to a battery reversing switch, not shown, associated with the track relay R195 associated with the track section 64 of the main railway track 60. Accordingly, the polarized relay R175 occupies its fully operated position, thereby to retain completed, at RA176, an obvious path for applying negative battery potential to the conductor C501 25 of the line 500 and, at RA177 and RA178, obvious paths for applying positive battery potential to the conductors C502 and C503 of the line 501. When negative battery potential is applied to the conductor C501 and positive battery potential is applied to the conductors C502 and C503 of the line 501 extending to the signal A associated with the main railway track 60, the signal A is operated to display a clear indication in a well known manner. Furthermore, it is noted 30 that the fully operated polarized relay R160 retains completed, at RA164, an obvious path for applying negative battery potential to the conductor C511 of the line 510 and retains interrupted, at RA167, an obvious path for applying positive battery potential to the conductor C512 of the line 510. When negative battery potential is connected to the conductor C511 and positive battery potential is disconnected from the conductor C512 of the line 510 extending to the 35 signal B associated with the main railway track 60, the signal B is operated to display a stop indication.

Furthermore, at the waystation 21, the track relay R210 associated with the track section 55 of the main railway track 50 occupies its operated position, this relay being energized by way of an obvious circuit including the winding thereof and the battery associated with the track section 55. The operated track relay R210 retains completed, at RA211 and RA212, a circuit for energizing the winding of the control relay R215, this circuit extending from the positive terminal of battery by way of RA212, the winding of R215 and RA211 to the negative terminal of battery. Accordingly, the control relay R215 occupies its operated position, thereby to retain completed, at RA216, an obvious circuit for energizing the winding of the control relay R220, thus retaining the last-mentioned relay in its operated position.

Furthermore, at this time, the clear relay R235 occupies its operated position due to a completed holding circuit for energizing the winding thereof, this circuit extending from the positive terminal of battery by way of the resistor 299,

RA233 and the back contact associated therewith, RA 238 and the front contact associated therewith, RA242, C280 and the winding of R235 to battery. The operated clear relay R235 and the restored siding relay R230 retain completed a circuit for energizing the winding of the polarized relay R250, this circuit extending from the positive terminal of battery by way of RA232 and the back contact associated therewith, RA237 and the front contact associated therewith, C291, the winding of R250, C290, RA236 and the front contact associated therewith, and RA231 and the back contact associated therewith to the negative terminal of battery. Accordingly, the polarized relay R250 occupies its fully operated position and retains completed, at RA252, an obvious path for applying negative battery potential to the conductor C296 of the line 295 and, at RA253 and RA254, obvious paths for applying positive battery potential to the conductors C297 and C298 of the line 295. When negative battery potential is applied to the conductor C296 and positive battery potential is applied to the conductors C297 and C298 of the line 295 extending to the signal F associated with the main railway track 50, the signal F is operated to display a clear indication.

Accordingly, at this time, the automatic block signals E, G, H, etc., associated with the main railway track 50 are operated to display clear indications; the automatic block signals C, A, etc., associated with the main railway track 60 are operated to display clear indications; the signal F associated with the main railway track 50 for directing traffic on the side railway track 70 is operated to display a clear indication; the signal B associated with the main railway track 60 for directing traffic on the side railway track 80 is operated to display a stop indication; and the signal D associated with the branch railway track 90 is operated to display a clear indication. As previously noted, the signal F associated with the main railway track 50 directs traffic on the side railway track 70 communicating with the main railway track 50 and is adapted to display one of three indications, namely a clear indication, indicating to a train proceeding along the main railway track 50 that it is not to take the side railway track 70; a take-siding indication, indicating to a train proceeding along the main railway track 50 that it is to take the side railway track 70; and a stop indication, indicating to a train proceeding along the main railway track 50 that it is to stop before proceeding beyond the junction between the main railway track 50 and the side railway track 70.

Similarly, the signals A and B associated with the main railway track 60 direct traffic on the side railway track 80 communicating with the main railway track 60 and are adapted to display coordinate indications. More specifically, the signal A is adapted to display three indications, namely, clear, caution and stop indications; while the signal B is adapted to display two indications, namely, stop and take-siding indications. More particularly, the signals A and B are so coordinated that the signal B displays a stop indication when a train proceeding along the main railway track 60 is not to take the side railway track 80; while the signal A, at this time, may display any one of its three indications, depending upon the condition of the succeeding track sections of the main railway track 60, in a well-known manner. The signal A will be operated to display a stop indication

and the signal B will be operated to display a take-siding indication when a train proceeding along the main railway track 60 is to take the side railway track 80. Finally, when both of the signals A and B display stop indications to a train proceeding along the main railway track 60, the train is signaled to stop before proceeding beyond the junction between the main railway track 60 and the side railway track 80.

Assuming now that a westbound train is traveling along the main railway track 50, the automatic block signals H, G, etc., will be operated in order to display appropriate indications, thereby to prevent a following train from entering the same track section with the reference train in a well-known manner. When the reference train enters the track section 55, the rolling stock of the train completes an obvious path between the track rails for short-circuiting the winding of the track relay R210, thereby to cause the track relay R210 to restore. Upon restoring, the track relay R210 interrupts, at RA211 and RA212, points in the previously traced circuit for energizing the winding of the control relay R215, thereby to cause the last-mentioned relay to restore. Upon restoring, the control relay R215 interrupts, at RA216, a point in the previously mentioned circuit for energizing the winding of the control relay R220; however, the last-mentioned relay, being of the slow-to-release type, does not immediately restore. Also, upon restoring, the control relay R215 completes, at RA217, a circuit for energizing the winding of the start relay R465 included in the order signaling apparatus 400. The last-mentioned circuit extends from the positive terminal of battery by way of RA217, C270 and the winding of R465 to the negative terminal of battery. When energized over the above-traced circuit, the start relay R465 operates to complete, at RA466, an obvious path for applying positive battery potential to the conductor C590, thereby to complete obvious circuits for energizing in multiple the windings of the control relays R440 and R450, whereupon the last-mentioned relays operate.

Upon operating, the control relay R440 prepares, at RA442, a point in a path, traced hereinafter, for applying positive battery potential to the conductor C589, prepares, at RA443, a point in a holding circuit, traced hereinafter, for energizing the winding of the control relay R430, prepares, at RA444, a point in a holding circuit for energizing the winding of the control relay R440, and prepares, at RA445, a point in a holding circuit, traced hereinafter, for energizing the winding of the control relay R450. Finally, the control relay R440 completes, at RA441, an impulsive circuit for transmitting impulses from the order signaling apparatus 400 by way of the telephone line 40 to the dispatcher station 30. The last-mentioned circuit extends from the line conductor C41 of the telephone line 40 by way of the choke coil 258, C281, the adjustable resistor 446, the condenser 447, RA426, RA441, the winding 438 of the repeater 436, C583, C286, the condenser 256 and the choke coil 257 to the line conductor C42 of the telephone line 40. Upon operating, the control relay R450 prepares, at RA453, a further point in the previously mentioned holding circuit for energizing the winding thereof and interrupts, at RA452, a point in a circuit, traced hereinafter, for energizing the winding of the control relay R455, thereby to

prevent operation of the last-mentioned relay at this time.

Shortly after the winding of the control relay R220 is deenergized, the last-mentioned relay restores to complete, at RA221, a circuit for energizing the winding of the start relay R460 in the order signaling apparatus 400. The last-mentioned circuit extends from the positive terminal of battery by way of RA221, C271 and the winding of R460 to the negative terminal of battery. When energized over the above-traced circuit, the start relay R460 operates to complete, at RA461, an obvious path for applying positive battery potential to the conductor C591, thereby to complete an obvious circuit for energizing the winding of the control relay R430. When energized over the above-traced circuit, the control relay R430 operates to complete, at RA433, the previously mentioned holding circuit for energizing the winding thereof, this circuit extending from the positive terminal of battery by way of RA428, RA433, RA443, C591 and the winding of R430 to the negative terminal of battery. Also, the control relay R430 completes, at RA434, the previously mentioned holding circuit for energizing the winding of the control relay R440. This circuit extends from the positive terminal of battery by way of RA428, RA434, RA444, C590 and the winding of R440 to the negative terminal of battery. Further, the control relay R430 completes, at RA435, the previously mentioned holding circuit for energizing the winding of the control relay R450, this circuit extending from the positive terminal of battery by way of RA428, RA435, RA445, RA453 and the winding of R450 to the negative terminal of battery. Further, the control relay R430 completes, at RA431, a multiple path in the impulsive circuit around the switch spring RA441 and completes, at RA432, the previously mentioned path for applying positive battery potential to the conductor C589, this path extending from the positive terminal of battery by way of RA442, RA432 and RA427 and the back contact associated therewith to the conductor C589. It is noted that the control relays R430, R440 and one of the control relays R450 or R455 are locked in their operated positions under the control of the stop relay R425 subsequent to the final operations of the control relays R430 and R440. The particular one of the control relays R450 or R455 which is locked in its operated position under the control of the stop relay R425 is dependent upon which one of the start relays R460 and R465 is first operated. In the present instance, the start relay R465 is always operated prior to the start relay R460, due to the slow-to-release characteristic of the control relay R220. Accordingly, the control relay R450 always operates and prevents operation of the control relay R455. In the event that it is desired that the control relay R455 operate first and prevent operation of the control relay R450, it is only necessary to cause the operation of the start relay R460 prior to the operation of the start relay R465. This may be accomplished by cross-connecting the conductors C270 and C271 included in the respective operating circuits of the start relays R465 and R460 for a purpose more fully described hereinafter.

The operated control relay R450 completes, at RA451, a connection between the conductor C589 and the contact bank 401 of the rotary switch 401, this connection extending from the conductor C589 by way of RA451 and C581 to the contact bank 401 of the rotary switch 401. On the

other hand, prevention of the operation of the control relay R455 by the operation of the control relay R450 prevents the conductor C589 from being connected to the contact bank 406 of the rotary switch 401. The last-mentioned connection would be completed in the event the control relay R455 were operated and would extend from the conductor C589 by way of RA456 and C580 to the contact bank 406 of the rotary switch 401. Thus, it is apparent that the contact banks 406 and 407 of the rotary switch 401 may be alternatively connected to the conductor C589 by causing appropriate operation of one of the control relays R450 or R455, while the last-mentioned operation may be governed by cross-connecting the conductors C270 and C271 included in the respective operating circuits of the start relays R465 and R460.

In the present instance, positive battery potential appearing upon the conductor C589 is connected by way of the previously traced connection to the contact bank 407 of the rotary switch 401; while the previously traced connection between the conductor C589 and the contact bank 406 of the rotary switch 401 is interrupted at RA456. At this point it is noted that the contacts in the contact bank 406 of the rotary switch 401 are multiplied together and connected to the conductor C580 in accordance with a Morse code corresponding to the letter E; the contacts in the contact bank 407 of the rotary switch 401 are multiplied together and connected to the conductor C581 in accordance with a Morse code corresponding to the letter W; while the contacts in the contact banks 408 and 409 of the rotary switch 401 are respectively multiplied together to the conductor C588 in accordance with Morse codes corresponding to the letters A and B, respectively. Further, it is noted that the conductor C588 is connected to the conductor C589; while the conductors C580 and C581 are adapted to be alternatively connected to the conductor C589. From the foregoing, it is apparent that when the shaft of the rotary switch 401 is rotated one revolution the various contact banks and associated wipers cause a code signal to be impressed between the conductors C587 connected to the various wipers of the rotary switch 401 and the conductor C589 corresponding to the letters A, B and E or A, B and W, depending upon which of the start relays R460 or R465 is first operated as previously explained. In the present instance, the relay R465 is first operated; accordingly, the one revolution of the shaft of the rotary switch 401 is effective to cause code signals corresponding to the letters A, B and W to be impressed between the conductors C587 and C589.

Also, the application of positive battery potential to the conductor C589 completes a circuit for energizing the winding of the step relay R415, this circuit extending from positive battery potential appearing upon the conductor C589 by way of C588, MA411 and the winding of R415 to the negative terminal of battery. When energized over the above-traced circuit, the step relay R415 operates to complete, at RA416, a circuit for energizing the winding of the motor magnet M410 of the rotary switch 401, this circuit extending from positive battery potential appearing upon the conductor C589 by way of C588, RA416, and the winding of M410 to the negative terminal of battery. When energized over the above-traced circuit, the motor magnet M410 conditions the wipers noted of the

rotary switch 401 to be driven one step in the counterclockwise direction and interrupts, at MA411, the previously traced circuit for energizing the winding of the step relay R415, thereby to cause the latter relay to restore. Upon restoring, the step relay R415 interrupts, at RA416, the previously traced circuit for energizing the winding of the rotary magnet M410, thereby to cause the rotary magnet M410 to restore. When the rotary magnet M410 restores, it drives the wipers noted of the rotary switch 401 one step in the counterclockwise direction and recombines, at MA411, the previously traced circuit for energizing the winding of the step relay R415. The step relay R415 and the rotary magnet M410 interact in the above manner, thereby to cause the wipers noted of the rotary switch 401 to be driven step by step in the counterclockwise direction a number of revolutions and continuously until the stop relay R425 is operated in a manner more fully described hereinafter.

Also, the application of positive battery potential to the conductor C589 completes an obvious circuit for energizing the lower winding of the impulse relay R420, thereby to cause the last-mentioned relay to operate and prepare, at RA421, a circuit for energizing the upper winding thereof by way of the conductor C587 connected to the wipers noted of the rotary switch 401. When one of the wipers noted of the rotary switch 401 engages one of the associated contacts having positive battery potential appearing thereon, the previously mentioned circuit for energizing the upper winding of the impulse relay R420 is completed, this circuit extending from positive battery potential appearing upon the contact engaged by the particular wiper by way of the particular wiper, the conductor C587, RA421 and the upper winding of R420 to the negative terminal of battery. When the upper winding of the impulse relay R420 is thus energized, the impulse relay R420, being of the differential type, restores to interrupt, at RA421, the previously traced circuit for energizing the upper winding thereof, whereupon the impulse relay R420 reoperates. Accordingly, when any one of the wipers noted of the rotary switch 401 engages a contact having positive battery potential appearing thereon, the impulse relay R420 rapidly operates and restores.

It is noted that a circuit is provided for energizing the primary winding 437 of the repeater 436 which extends from the positive terminal of battery by way of the primary winding 437, C582, the resistor 448, the condenser 449 and the resistor 454 to the negative terminal of battery. Accordingly, positive battery potential is applied by way of a portion of the previously traced circuit to one terminal of the condenser 449 and positive and negative battery potentials are alternately applied to the other terminal of the condenser 449, negative battery potential being applied thereto by way of the resistor 454 and positive battery potential being applied thereto by way of the switch spring RA421. Hence, the condenser 449 is rapidly charged and discharged in accordance with the intermittent operation of the impulse relay R420, thereby to cause corresponding signal currents to traverse the primary winding 437 of the repeater 436. These signal currents traversing the primary winding 437 of the repeater 436 induce corresponding signal currents in the secondary winding 438 of the repeater 436 included in the impulse circuit con-

nected across the line conductors C41 and C42 of the telephone line 40. Accordingly, signal currents traverse the winding 304 of the repeater 302 at the dispatcher station 30 and induce corresponding currents in the associated winding 303 of the repeater 302 connected by way of the coupling unit 301 to the telephone instrument 300 thereat. Accordingly, the telephone instrument 300 operates to produce coded tones in accordance with the operation of the order signaling apparatus 400 at the way-station 21 in a well known manner. Specifically, in the present instance, the order signaling apparatus 400 operates to cause coded tones corresponding to the letters A, B, W to be transmitted by way of the telephone line 40 to the telephone instrument 300 at the dispatcher station 30, thereby to indicate to the dispatcher thereat that a westbound train proceeding along the main railway track 50 has entered the track section 55 of the main railway track 50 associated with the waystation 21.

After the dispatcher at the dispatcher station 30 has received a number of times the signal transmitted from the order signaling apparatus 400 at the waystation 21, he waits an adequate time interval in order to give the reference train an opportunity to clear the track section 55 of the main railway track 50 and then arrests further operation of the order signaling apparatus 400 by actuating the corresponding impulsing key K340. When the impulsing key K340 at the dispatcher station 30 is operated, the toothed cam 341 thereof rotates one revolution, thereby to cause a series of digits to be transmitted over the telephone line 40, in a manner more fully described hereinafter, in order to cause the selector switches 185, 260, etc., at the waystations 20 and 21, etc., to be operated to corresponding positions in order to effect the release of the operated order signaling apparatus 400 at the waystation 21 in a manner more fully described subsequently. Specifically, when the impulsing key K340 at the dispatcher station 30 is operated, the toothed cam 341 thereof continuously engages the associated switch spring 342, and causes the last-mentioned switch spring to engage intermittently the associated switch spring 343, thereby to cause positive battery potential to be steadily applied to the switch spring 342 and to be applied intermittently to the switch spring 343. The intermittent application of positive battery potential to the switch spring 343 corresponds to the various digits of the code transmitted from the impulsing key K340. The steady application of positive battery potential to the switch spring 342 completes an obvious circuit for energizing the winding of the control relay R385, thereby to cause the last-mentioned relay to operate and remain operated during the duration of the code transmitted; while the intermittent application of positive battery potential to the switch spring 343 completes intermittently an obvious circuit for energizing the winding of the impulse relay R375, thereby to cause the last-mentioned relay to operate and restore in accordance with the digits of the code transmitted. Upon operating, the control relay R385 completes, at RA386 and RA387, a circuit for energizing the winding 303 of the repeater 302, this circuit extending from the positive terminal of battery by way of RA377 and the back contact associated therewith, RA387, the coupling unit 301, the winding 303, the coupling unit 301, RA386 and RA376 and the back contact associated therewith to the nega-

tive terminal of battery. When the impulse relay R375 operates, it interrupts, at RA376 and the back contact associated therewith and at RA377 and the back contact associated therewith, the previously traced circuit for energizing the winding 303 of the repeater 302 and completes, at RA376 and the front contact associated therewith and at RA377 and the front contact associated therewith, an alternative circuit for energizing the winding 303 of the repeater 302. The 10 alternative circuit for energizing the winding 303 of the repeater 302 extends from the positive terminal of battery by way of RA376 and the front contact associated therewith, RA386, the coupling unit 301, the winding 303 of the repeater 302, the coupling unit 301, RA387 and RA377 and the front contact associated therewith to the negative terminal of battery. Accordingly, as the 15 impulse relay R375 operates and restores, the previously traced circuits are completed alternately, thereby to cause battery potential to be reversed over the winding 303 of the repeater 302 in accordance with the code transmitted. The surges of currents flowing in the winding 303 of the repeater 302, as a result of the reversal of battery thereover produced by the intermittent operation of the impulse relay R375, cause corresponding surges of current to be induced in the winding 304 of the repeater 302 connected 20 across the line conductors C41 and C42 of the telephone line 40.

The impulse code thus transmitted from the impulsive key K304 at the dispatcher station 30 over the telephone line 40 causes the selector switches 185, 260, etc., to be operated to corresponding positions in accordance with the code transmitted. For example, the circuit for energizing the winding of the motor magnet M280 of the selector switch 260 extends from the line conductor C41 of the line 40 by way of the choke coil 258, the winding of M280, the condenser 256 and the choke coil 257 to the line conductor C42 of the telephone line 40. More specifically, the wiper 261 of the selector switch 260 is operated to a position engaging the contact in the associated contact bank terminating the conductor C283, whereupon a circuit is completed for energizing in series the stop relay R425 in the order signaling apparatus 400 and the control relay R245, this circuit extending from the positive terminal of battery by way of the winding of R245, the wiper 261 of the selector switch 260, the contact in the associated contact bank terminating the conductor C283, C283 and the winding of R425 to the negative terminal of battery. When energized over the above-traced circuit, the control relay R245 and the stop relay R425 operate. It is noted that although the selector switches 185, etc., at the waystation 20, etc., respectively are operated to corresponding positions, the wipers thereof do not engage control contacts at these positions; only the selector switch 260 at the waystation 21 terminates a control contact at this position. Upon operating, the stop relay R425 interrupts, at RA426, the previously traced circuit for energizing the primary winding 438 of the repeater 436, interrupts, at RA427 and the back contact associated therewith, the secondary traced path for applying positive battery potential to the conductor C589 and completes, at RA427 and the front contact associated therewith, a holding circuit for energizing the winding thereof. The last-mentioned circuit extends from the positive termi-

nal of battery by way of RA442, RA432, RA421 and the front contact associated therewith, and the winding of R425 to the negative terminal of battery. Although the control relay R245 operates at this time, it has no function to perform.

After the impulsive key K340 at the dispatcher station 30 has operated to transmit the code corresponding thereto, the toothed cam 341 and the switch springs 342 and 343 thereof are moved into respective disengagements, thereby to interrupt the previously traced circuits for energizing the winding of the control relay R385 and the winding of the impulse relay R375, in order to cause these relays to restore. When the control relay R385 restores, it interrupts, at RA386 and at RA387, points in the previously traced circuit for applying positive and negative battery potentials to the coupling unit 301, whereupon alternating 20 ringing current is not projected from the coupling unit 301 over the telephone line 40. Accordingly, each of the selector switches 185, 260, etc., restore to their normal positions. When the selector switch 260 restores to its normal position, the previously traced circuit for energizing the winding of the control relay R245 in series with the winding of the stop relay R425 is interrupted, thereby to cause the control relay R245 to restore. When positive battery potential is removed from the conductor C589 in the order signaling apparatus 400, the previously 25 traced circuits for energizing the lower winding of the impulse relay R420, the winding of the step relay R415, and the winding of the motor magnet M410 are interrupted, thereby to cause these relays and the motor magnet M410 to restore. Also, upon operating, the stop relay R425 interrupts, at RA428, the previously traced holding 30 circuits for energizing the windings of the control relays R430, R440 and R450, thereby to cause these relays to restore. Upon restoring, the control relays R430 and R440 interrupt, at RA432 and RA442, respectively, points in the 35 previously traced holding circuit for energizing the winding of the stop relay R425, thereby to cause the last-mentioned relay to restore.

Prior to the time the dispatcher at the dispatcher station 30 operates the impulsive key K340 in order to cause the order signaling apparatus 400 to restore, as explained above, the reference train has cleared the track section 55 of the main railway track 50 as previously noted, thereby to cause the track relay R210 to reoperate. Upon reoperating, the track relay R210 40 completes, at RA211 and RA212, the previously traced circuit for energizing the winding of the control relay R215, thereby to cause the last-mentioned relay to reoperate. Upon reoperating, the control relay R215 interrupts, at RA217, the previously traced circuit for energizing the start relay R465 in the order signaling apparatus 400, thereby to cause the last-mentioned relay to restore. Further, the control relay R215 45 completes, at RA216, the previously mentioned circuit for energizing the winding of the control relay R220, thereby to cause the last-mentioned relay to reoperate and interrupt, at RA221, the previously traced circuit for energizing the winding of the start relay R468 in the order signaling apparatus 400 in order to cause the last-mentioned relay to restore. At this time the order signaling apparatus 400 is completely released and the dispatcher at the dispatcher station 30 50 has been advised that the reference train has

cleared the track section 55 of the main railway track 50 associated with the waystation 21.

At this time the signal F is operated to display a clear indication and the lamp L334 at the dispatcher station 30 is illuminated, thereby to indicate the operated position of the signal F as previously noted. In the event the dispatcher at the dispatcher station 30 desires that the reference train proceeding along the main railway track 50 toward the side railway track 70 take the side railway track 70, he operates the corresponding siding impulsing key K325. When the impulsing key K325 is operated, the toothed cam 326 thereof constantly engages the associated switch spring 327 and the last-mentioned switch spring intermittently engages the associated switch spring 328 in accordance with the code to be transmitted, such code being determined by the position of the teeth upon the toothed cam 326 as previously explained. When the toothed cam 326 engages the associated switch spring 327, obvious circuits for energizing the winding of the siding relay R365 and for illuminating the lamp L329 are completed, thereby to cause the last-mentioned relay to operate. Upon operating, the sliding relay R365 interrupts, at RA366, a point in a holding circuit for energizing the winding of the stop relay R360, interrupts, at RA367 and the back contact associated therewith, the previously traced holding circuit for energizing the winding of the clear relay R370 and the previously traced circuit for illuminating the lamp L334, prepares, at RA367 and the front contact associated therewith, a point in a holding circuit, traced hereinafter, for energizing the winding of the siding relay R365 and a circuit, traced hereinafter, for illuminating the lamp L329. The above-mentioned holding circuit for energizing the winding of the siding relay R365 and the circuit for illuminating the lamp L329 are not immediately completed due to the fact that the clear relay R370 does not immediately restore when the holding circuit for energizing the winding thereof is interrupted, the last-mentioned relay being of the slow-to-release type.

Also, upon operating, the siding relay R365 completes, at RA368 and the front contact associated therewith, a circuit for energizing the winding of the control relay R390, this circuit extending from the positive terminal of battery by way of RA368 and the front contact associated therewith, RA362 and the back contact associated therewith, RA374 and the front contact associated therewith, and the winding of R390 to the negative terminal of battery. When energized over the above-traced circuit, the control relay R390 operates to complete, at RA391, a holding circuit for energizing the winding thereof, this circuit extending from the positive terminal of battery by way of the switch spring 396 and the front contact associated therewith of the key K395, RA391 and the winding of R390 to the negative terminal of battery. Subsequent to the operation of the control relay R390, the clear relay R370 restores, thereby to prepare, at RA371, a point in the previously mentioned holding circuit for energizing the winding of the stop relay R360, to interrupt, at RA373, a further point in the previously traced holding circuit for energizing the winding of the clear relay R370, to interrupt, at RA374 and the front contact associated therewith, a point in the previously traced original circuit for energizing the winding 75

of the control relay R390, and to complete, at RA372, the previously mentioned holding circuit for energizing the winding of the siding relay R365 and the circuit for illuminating the lamp L329. The holding circuit for energizing the winding of the siding relay R365 extends from the positive terminal of battery by way of RA361 and the back contact associated therewith, RA367 and the front contact associated therewith, RA372 and the winding of R365 to the negative terminal of battery; while the circuit for illuminating the lamp L329 extends from the positive terminal of battery by way of RA361 and the back contact associated therewith, RA367 and the front contact associated therewith, RA372 and the lamp L329 to the negative terminal of battery.

Also, upon operating, the control relay R390 completes, at RA394, an obvious circuit for energizing the winding of the control relay R385, thereby to cause the last-mentioned relay to operate and complete, at RA386 and at RA387, the previously traced circuit for energizing the winding 303 of the repeater 302. Further, the control relay R390 completes, at RA393, a circuit for energizing the winding of the impulse relay R375 and completes, at RA392, a circuit for energizing the winding of the control relay R380. The circuit for energizing the winding of the impulse relay R375 extends from the positive terminal of battery by way of the toothed cam 326 and the switch springs 327 and 328 of the impulsing key K325, RA393 and the winding of R375 to the negative terminal of battery. The circuit for energizing the winding of the control relay R380 extends from the positive terminal of battery by way of the toothed cam 326 and the switch springs 327 and 328 of the impulsing key K325, RA392 and the winding of R380 to the negative terminal of battery. As previously noted, during the operation of the toothed cam 326 of the impulsing key K325, the associated switch springs 327 and 328 are intermittently operated into engagement. Accordingly, the previously traced circuits for energizing the winding of the impulse relay R375 and the winding of the control relay R380 are intermittently completed. Hence, the impulse relay R375 operates intermittently in order to cause the repeater 301 to repeat corresponding impulses over the telephone line 40 as previously explained. Furthermore, due to the fact that the control relay R380 is of the slow-to-operate type, it does not immediately operate.

Just at the conclusion of the operation of the impulsing key K325, the slow-to-operate control relay R380 operates. Upon operating, the control relay R380 completes, at RA381, holding circuits for energizing in multiple the winding of the control relay R380 and the winding of the impulsing relay R375. The last-mentioned circuits extend from RA394 by way of RA381 and the winding of R380 to the negative terminal of battery and from RA394 by way of RA381, RA392, RA393 and the winding of R375 to the negative terminal of battery. Accordingly, at this time, the impulsing key K325 has completed its revolution, thereby to cause the repeater 302 to repeat a corresponding impulse code over the telephone line 40; and the control relays R380, R385, R390 and the impulse relay R375 occupy their operated positions. At the conclusion of the impulsing, when the impulse relay R375 and the control relay R385 occupy their operated positions, positive and negative battery potentials are connected to the coupling unit 301 as previously explained. At this time the

ring circuit included in the coupling unit 301 is operatively connected to the winding 303 of the repeater 302, thereby to cause ringing current to be projected over the telephone line 40 in order to retain in its operated position an operated one of the selector switches associated with the telephone line 40 at one of the waystations in a manner more fully described hereinafter. The impulses of the code transmitted over the telephone line 40 at this time cause the selector switches 185, 260, etc., disposed at the waystations 20, 21, etc., to be operated to corresponding positions; however, only the selector switch 260 disposed at the waystation 21 is operated to cause the wiper thereof to engage a contact in the associated contact bank terminating a control conductor as previously explained. Specifically, in the present instance, the wiper 261 of the selector switch 260 engages the contact in the associated contact bank terminating the control conductor C281 extending to the siding relay R230. Accordingly, only the selector switch 260 is completely operated. Hence, only this selector switch is retained in its operated position by the ringing current projected over the telephone line 40 at the conclusion of the code, the remainder of the selector switches being restored to their normal positions.

When the wiper 261 of the selector switch 260 engages the contact in the associated contact bank terminating the control conductor C281, a circuit is completed for energizing in series the winding of the control relay R245 and the winding of the siding relay R230, this circuit extending from the positive terminal of battery by way of the winding of R245, the wiper 261 and the associated contact terminating the control conductor C281, C281 and the winding of R230 to the negative terminal of battery. When energized over the above-traced series circuit, the control relay R245 and the siding relay R230 operate.

Upon operating, the siding relay R230 interrupts, at RA233 and the back contact associated therewith, the previously traced holding circuit for energizing the winding of the clear relay R235, thereby to cause the last-mentioned relay to restore. Further, the siding relay R230 interrupts, at RA231 and the back contact associated therewith and at RA232 and the back contact associated therewith, points in the previously traced circuit for energizing the winding of the polarized relay R250 and prepares, at RA231 and the front contact associated therewith and at RA232 and the front contact associated therewith, points in an alternative circuit, traced hereinafter, for energizing the winding of the polarized relay R250. Further, the siding relay R230 prepares, at RA233 and the front contact associated therewith, a point in a holding circuit, traced hereinafter, for energizing the winding thereof and prepares, at RA234, a point in a marking circuit, traced hereinafter, for the contact bank 475 of the rotary switch 471 in the answer-back apparatus 470. As previously noted, substantially immediately the siding relay R230 operates, the clear relay R235 restores, thereby to complete, at RA239, the previously mentioned holding circuit for energizing the winding of the siding relay R230. The last-mentioned circuit extends from the positive terminal of battery by way of the resistor 299, RA233 and the front contact associated therewith, RA239, RA243, C281 and the winding of R230 to the negative terminal of battery. Further, the clear relay R235 inter-

rupts, at RA238 and the front contact associated therewith, a further point in the previously traced holding circuit for energizing the winding thereof and prepares, at RA238 and the back contact associated therewith, a point in a holding circuit for energizing the winding of the stop relay R240. Finally, the clear relay R235 completes, at RA236 and the back contact associated therewith and at RA237 and the back contact associated therewith, the previously mentioned alternative circuit for energizing the winding of the polarized relay R250. The last-mentioned circuit extends from the positive terminal of battery by way of RA232 and the front contact associated therewith, RA236 and the back contact associated therewith C290, the winding of R250, C291, RA237 and the back contact associated therewith, and RA231 and the front contact associated therewith to the negative terminal of battery.

As a consequence of the operation of the siding relay R230 and the restoration of the clear relay R235, the first-mentioned circuit for energizing the winding of the polarized relay R250 is interrupted and the above-traced alternative circuit for energizing the winding of the polarized relay R250 is completed. More specifically, battery potential is reversed over the winding of the polarized relay R250, thereby to cause the polarized relay R250 to restore only the contact springs RA254 and RA255. When the contact spring RA254 of the polarized relay R250 is restored, the previously traced path for applying positive battery potential to the conductor C298 of the line 295 extending to the signal F is interrupted, thereby to cause the signal F to be operated to display a take-siding indication. When the contact spring RA255 of the polarized relay R250 is restored, a point in a marking circuit for the contact bank 477 of the answer-back apparatus 470 is interrupted.

When the signal F is operated from its previous position to display a clear indication to its present position to display a take-siding indication, the mechanical switch S225 associated therewith is actuated. More particularly, the wiper 221 of the switch S225 is actuated to disengage the contact terminating the conductor C273, thereby to interrupt an additional point in a marking circuit for the contact bank 477 of the rotary switch 471 in the answer-back apparatus 470; and to engage the contact terminating the conductor C274, thereby to complete the previously mentioned marking circuit for the contact bank 475 of the rotary switch 471 in the answer-back apparatus 470. An additional point in the previously mentioned marking circuit for the contact bank 475 of the rotary switch 471 in the answer-back apparatus 470 was prepared at RA246 upon the operation of the control relay R245. The completed marking circuit for the contact bank 475 of the rotary switch 471 in the answer-back apparatus 470 extends from the negative terminal of battery by way of RA246, RA251 and the front contact associated therewith, the wiper 221 of the switch S225, the contact terminating the conductor C274, C274, RA234 and C273 to the multiplied contacts in the contact bank 475 of the rotary switch 471 in the answer-back apparatus 470.

Also, upon operating, the control relay R245 completes, at RA247, an obvious path for applying negative battery potential to the conductor C276; thereby to complete obvious multiple circuits for energizing the upper winding of the

impulse relay R480 and the winding of the step relay R485 in the answer-back apparatus 470. When thus energized, the step relay R485 operates to complete, at RA486, an obvious circuit for energizing the winding of the motor magnet M490 from negative battery potential appearing upon the conductor C276, thereby to cause the motor magnet M490 to operate. Upon operating, the motor magnet M490 conditions the wipers 472, 473 and 474 of the rotary switch 471 to be 10 driven one step in the clockwise direction and interrupts, at MA491, a point in the previously mentioned circuit for energizing the winding of the step relay R485, thereby to cause the last-mentioned relay to restore. Upon restoring, the step relay 15 interrupts, at RA486, a point in the previously mentioned circuit for energizing the winding of the motor magnet M490, thereby to cause the motor magnet M490 to restore. Upon restoring, the motor magnet M490 drives the wipers noted of the rotary switch 471 one step in the clockwise direction and recomplete, at MA491, the previously mentioned circuit for 20 energizing the winding of the step relay R485. The step relay R485 and the motor magnet M490 interact in the above-described manner, thereby to drive the wipers noted of the rotary switch 471 step by step in the clockwise direction.

When the upper winding of the impulse relay R480 is thus energized, this relay operates to 25 prepare, at RA481, a point in a circuit, traced hereinafter, for energizing the lower winding thereof. When the wiper 472 engages a contact in the associated contact bank 475 of the rotary switch 471, the previously mentioned circuit for energizing the lower winding of the impulse relay R480 is completed, this circuit extending from negative battery potential appearing upon the conductor C278 by way of the multiplied contacts in the contact bank 475, the wiper 472, C586, 40 RA481 and the lower winding of R480 to the positive terminal of battery. When the lower winding of the impulse relay R480 is thus energized, the last-mentioned relay restores, this relay being of the differential type. Upon restoring, the 45 impulse relay R480 interrupts, at RA481, the previously traced circuit for energizing the lower winding thereof, thereby to cause the last-mentioned relay to reoperate, whereupon the previously traced circuit for energizing the lower winding thereof is recompleted at RA481. Accordingly, the impulse relay R480 operates and 50 restores rapidly, while the wiper 472 engages a contact in the associated contact bank 475 of the rotary switch 471 multiplied to the conductor C278 having negative battery potential thereon. It is noted that the primary winding 463 of the repeater 462 is included in an operating circuit 55 extending from the negative terminal of battery by way of the winding 463, the condenser 468, C585 and the resistor 478 to the positive terminal of battery. Accordingly, one terminal of the condenser 468 is connected to the negative terminal of battery and the other terminal of the condenser 468 is connected to the positive terminal of battery, when the impulse relay R480 is restored, and connected to the negative terminal of battery, when the impulse relay R480 is operated. Accordingly, the rapid operation of the 60 impulse relay R480 causes the condenser 468 to be rapidly charged and discharged, whereby surges of current traverse the primary winding 463 of the repeater 462 in opposite directions. The surges of current traversing the primary winding 463 of the repeater 462 induce corre- 70

sponding surges of current in the secondary winding 464 thereof, thereby to cause corresponding surges of current to be transmitted over the telephone line 40. The circuit for transmitting current from the repeater 462 over the telephone line 40 extends from the line conductor C41 of the telephone line 40 by way of the choke coil 258, C281, C584, the secondary winding 464 of the repeater 462, the adjustable resistor 467, the condenser 459, C286, the condenser 256 and the choke coil 257 to the line conductor C42 of the telephone line 40. More specifically, it is noted that the contacts in the contact bank 475 are multiplied together to produce a Morse coded tone corresponding to the letter T. Accordingly, the operation of the answer-back apparatus 470 at this time is effective to cause a coded signal corresponding to the letter T to be transmitted therefrom over the telephone line 40 to the dispatcher station 30, which coded signal is repeated by the repeater 302 at the dispatcher station 30 to the telephone instrument 300 thereat. Accordingly, the dispatcher at the dispatcher station 30 hears the coded tone corresponding to the letter T a number of times as the answer-back apparatus repeatedly operates. The receipt of the coded tone corresponding to the letter T indicates to the dispatcher at the dispatcher station 30 that the signal F associated with the main railway track 50 at the waystation 21 has been operated to display a take-siding indication. Hence, the answer-back apparatus 470 operates to transmit a Morse coded signal over the telephone line 40 to the dispatcher station 30, which verifies the operated position of the signal F.

At this point it is noted that the contacts in the contact banks 476 and 477 of the rotary switch 471 are multiplied to the marking conductors C271 and C275, respectively, to cause Morse coded signals corresponding to the letters U and N, respectively, to be transmitted over the telephone line 40 to the dispatcher station 30 under certain conditions. Specifically, when the signal F is operated to display a stop indication, the answer-back apparatus 470 is operated to transmit a coded signal corresponding to the letter U over the telephone line 40; and when the signal F is operated to display a clear indication, the answer-back apparatus 470 is operated to transmit a coded signal corresponding to the letter N over the telephone line 40. The transmission of the coded signals corresponding to the letters U and N, respectively, indicate to the dispatcher at the dispatcher station 30 that the signal F has been operated to display stop and clear indications, respectively.

After the dispatcher at the dispatcher station 30 has received the coded tone transmitted from the answer-back apparatus 470 at the waystation 20 a number of times, thereby to verify the actual operated position of the signal F as determined by the mechanical switch S225 associated with the signal F with the desired operated position of the signal F as determined by the operation of the siding impulsing key K325 and the illumination of the lamp L329, he arrests operation of the answer-back apparatus 470 by actuating the key K395 at the dispatcher station 30 away from its normal position. When the key K395 at the dispatcher station 30 is operated away from its normal position, the previously traced holding circuit for energizing the winding of the control relay R390 is interrupted at the switch spring 396 and the associated front

contact, thereby to cause the control relay R390 to restore. Upon restoring, the control relay R390 interrupts, at RA394, the previously traced holding circuits for energizing the windings of the control relays R380 and R385 and the winding of the impulse relay R375, thereby to cause these relays to restore. When the control relay R385 restores, the previously traced circuits for applying positive and negative battery potentials to the coupling unit 301 are interrupted, whereupon the coupling unit interrupts the connection for projection of ringing current over the telephone line 40 in a well-known manner.

When the projection of ringing current over the telephone line 40 is interrupted, the operated selector switch 260 at the waystation 21 restores to its normal position, thereby to interrupt the previously traced series circuit for energizing the winding of the control relay R245 in series with the winding of the siding relay R230. The control relay R245 then restores; however, the siding relay R230 remains in its operated position due to the completed holding circuit for energizing the winding thereof. Upon restoring, the control relay R245 interrupts, at RA246, the previously traced marking circuit for the contact bank 475 of the rotary switch 471 in the answer-back apparatus 470. Finally, when the control relay R245 restores, it interrupts, at RA247, the previously mentioned path for applying negative battery potential to the conductor C276, thereby to interrupt the previously mentioned circuits for energizing the windings of the impulse relay R480, the step relay R485 and the motor magnet M490, whereupon the impulse relay R480, the step relay R485 and the motor magnet M490 restore in order to arrest further operation of the answer-back apparatus 470. At this time the signal F associated with the main railway track 50 occupies a position to display a take-siding indication to the reference train and the answer-back apparatus 470 is completely released for further use.

It is noted, at this point, that the selector switches 185, 260, etc., at the waystations 20, 21, etc., are operated in accordance with the impulses transmitted over the telephone line 40 from the dispatcher station 30; however, these selector switches are not operated in accordance with the Morse coded signals transmitted over the telephone line 40 from the order signaling apparatus and the answer-back apparatus disposed in the various waystations.

After the reference train has taken the side railway track 70, the dispatcher at the dispatcher station 30 may operate the signal F to display a clear or stop indication, as desired. For example, in order to operate the signal F to display a stop indication, the dispatcher at the station 30 operates the corresponding stop impulsing key K320, whereupon the apparatus at the dispatcher station 30 operates to cause appropriate impulses to be transmitted over the telephone line 40 in the previously described manner. The operation of the apparatus at the dispatcher station 30 causes the selector switch 260 at the waystation 21 to be actuated to a corresponding position, whereupon the control relay R245 and the stop relay R240 at the waystation 21 are energized in series circuit relationship. As a consequence of the operation of the stop relay R240, the operating circuit of the signal F is controlled in order to cause the signal F to be operated to display a stop indication in a manner similar to that previously described; and

as a consequence of the actual operation of the signal F to display a stop indication and the operation of the control relay R245, operation of the answer-back apparatus 470 is initiated. At this time the answer-back apparatus 470 operates to cause a coded tone corresponding to the letter U to be transmitted over the telephone line 40 to the dispatcher station 30, thereby to verify the actual operated position of the signal F with the desired operated position thereof. In order to arrest operation of the answer-back apparatus 470 at this time, the dispatcher at the dispatcher station 30 again operates the key K395 thereat away from its normal position as previously explained. Subsequently, the dispatcher at the dispatcher station 30 may operate the signal F to display a clear indication by operating the impulsing key K330. The subsequent operations of the apparatus incident to the operation of the clear impulsing key K330 are analogous to those previously described and will be readily understood. Accordingly, in the interest of brevity, the details of these operations are omitted.

Assuming now that an eastbound train is proceeding along the main railway track 60, when the train enters the track section 67, the rolling stock thereof completes an obvious path for short-circuiting the winding of the track relay R100, thereby to cause the last-mentioned track relay to restore. Upon restoring, the track relay R100 interrupts, at RA101 and RA102, the previously traced circuit for energizing the winding of the polarized relay R115 in series with the winding of the control relay R130, thereby to cause these relays to restore. Upon restoring, the polarized relay R115 interrupts, at RA116, at RA117 and at RA118, points in the previously traced paths for applying negative battery potential to the conductor C531 and positive battery potential to the conductors C532 and C533 of the line 530 extending to the signal D, thereby to cause the signal D associated with the branch railway track 90 to be operated to display a stop indication. The operation of the signal D to display a stop indication indicates to any train proceeding along the branch railway track 90 that it is not to enter the main railway track 60. Upon restoring, the control relay R130 interrupts, at RA131 and the front contact associated therewith and at RA132 and the back contact associated therewith, points in the previously traced circuit for energizing the winding of the polarized relay R135 and completes, at RA131 and the back contact associated therewith and at RA132 and the back contact associated therewith, an alternative circuit for energizing the winding of the polarized relay R135. The last-mentioned circuit extends from the positive terminal of battery by way of RA132 and the back contact associated therewith, C563, RA109, RA121, the winding of R135, RA122, RA108, C562 and RA131 and the back contact associated therewith to the negative terminal of battery. As a consequence of the restoration of the control relay R130, the previously traced original circuit for energizing the winding of the polarized relay R135 is interrupted and the above-traced alternative circuit for energizing the winding of the polarized relay R135 is completed. More particularly, battery potential is reversed over the winding of the polarized relay R135, thereby to cause this polarized relay to release its contact spring RA137, whereupon the previously traced circuit for energizing the winding of the control relay R140 is in-

terrupted. The control relay R140, being of the slow-to-release type, does not immediately restore; however, shortly thereafter it restores and completes, at RA141, an obvious path for applying positive battery potential to the conductor C550 extending to the order signaling apparatus 201. Further, the control relay R140 prepares, at RA142, a point in a path, traced hereinafter, for applying positive battery potential to the conductor C551 extending to the order signaling apparatus 201.

The reference train proceeding along the main railway track 60 next enters the track section 66, whereupon the rolling stock thereof completes an obvious path for short-circuiting the winding of the track relay R105, thereby to cause this track relay to restore. Upon restoring, the track relay R105 interrupts, at RA106 and at RA107, further points in the previously traced circuit for energizing the winding of the polarized relay R115 and interrupts, at RA108 and RA109, the previously traced alternative circuit for energizing the winding of the polarized relay R135, thereby to cause this polarized relay to restore. Upon restoring, the polarized relay R135 interrupts, at RA136 and the front contact associated therewith, a further point in the previously traced circuit for energizing the winding of the control relay R140 and completes, at RA136 and the back contact associated therewith, the previously mentioned path for applying positive battery potential to the conductor C551 extending to the order signaling apparatus 201. The last-mentioned path extends from the positive terminal of battery by way of RA136 and the back contact associated therewith and RA142 to the conductor C551. This application of positive battery potential, first to the conductor C550 and then to the conductor C551, these conductors extending to the order signaling apparatus 201, initiates operation of the order signaling apparatus 201, whereupon a Morse coded signal is transmitted therefrom by way of the line 515, the condenser 189 and the choke coils 190 and 191 to the telephone line 40 extending to the dispatcher station 30. The coded signal transmitted by the order signaling apparatus 201 over the telephone line 40 to the dispatcher station 30 causes the telephone instrument 300 thereat to be actuated to produce a coded tone corresponding to the signal transmitted. Specifically, the signal transmitted from the order signaling apparatus 201 to the telephone instrument 300 at the dispatcher station 30 corresponds to the letter E and two suitable signature letters, such, for example, as the letters C and D. Accordingly, the order signaling apparatus 201 operates, in the previously described manner, repeatedly to transmit signals corresponding to the letters E, C, D to the dispatcher station 30, thereby to indicate to the dispatcher thereat that an eastbound train proceeding along the main railway track 60 has entered the track section 66 thereof associated with the waystation 20.

After the dispatcher at the dispatcher station 30 has received the coded tone transmitted thereto from the order signaling apparatus 201 a number of times, he releases further operation of the order signaling apparatus by operating the corresponding impulsing key thereat. Specifically, the dispatcher at the dispatcher station 30 operates the impulsing key K335 thereat, thereby to cause corresponding impulses to be transmitted over the telephone line 40 in the previously described manner, whereupon the selector

switch 185 is operated to cause the wiper 186 thereof to engage the associated contact terminating the conductor C516 extending to the order signaling apparatus 201. When the wiper 186 engages the contact terminating the conductor C516, a circuit is completed for energizing in series the control relay R170 and a relay included in the order signaling apparatus 201 in a manner similar to that described in connection with the operation of the order signaling apparatus 400 disposed at the waystation 21. The operation of the relay included in the order signaling apparatus 201 causes the last-mentioned apparatus to be released, as previously explained, while the operation of the control relay R170 is without effect at this time. At the conclusion of the impulses transmitted over the telephone line 40, due to the operation of the impulsing key K335 at the dispatcher station 30, all of the selector switches 185, 260, etc., restore to their normal positions. When the selector switch 185 disposed at the waystation 20 restores to its normal position, the previously mentioned circuit for energizing in series the winding of the control relay R170 and the winding of the relay included in the order signaling apparatus 201 is interrupted, thereby to cause the control relay R170 to restore, the relay included in the order signaling apparatus being retained in its operated position until the order signaling apparatus 201 is completely released, as previously explained.

When the reference train proceeding along the main railway track 60 enters the track section 65, the rolling stock thereof completes an obvious path for short-circuiting the winding of the track relay R110, thereby to cause this track relay to restore. Upon restoring, the track relay R110 interrupts, at RA111 and the front contact associated therewith and RA112 and the front contact associated therewith, further points in the previously traced original circuit for energizing the winding of the polarized relay R115 in series with the winding of the control relay R130 and prepares, at RA111 and the back contact associated therewith and RA112 and the back contact associated therewith, an alternative circuit, traced hereinafter, for energizing the winding of the control relay R130 in series with the winding of the polarized relay R115. Further, the track relay R110 interrupts, at RA113 and at RA114, points in the previously traced circuit for energizing the winding of the polarized relay R120, thereby to cause the last-mentioned relay to restore. Upon restoring, the polarized relay R120 interrupts, at RA121 and at RA122, further points in the previously traced alternative circuit for energizing the winding of the polarized relay R135 and interrupts, at RA123, at RA124 and at RA125, points in the previously traced path for applying negative battery potential to the conductor C521 and positive battery potential to the conductors C522 and C523 of the line 520 extending to the signal C associated with the track section 65 of the main railway track 60, thereby to cause the signal C to operate to display a stop indication.

When the reference train has cleared the track sections 67 and 66 and is in the track section 65 of the main railway track 60, the track relays R100 and R105 reoperate and the track relay R110 remains in its restored position. Upon reoperating, the track relay R100 prepares, at RA101 and at RA102, points in the previously mentioned alternative circuit for energizing the

winding of the polarized relay R115 in series with the winding of the control relay R130; and, upon reoperating, the track relay R105 completes, at RA106 and RA107, this alternative circuit for energizing the winding of the polarized relay R115 in series with the winding of the control relay R130. The last-mentioned circuit extends from the positive terminal of battery by way of the winding of R130, RA112 and the back contact associated therewith, C561, RA107, RA102, the winding of R115, RA101, RA106 and RA111 and the back contact associated therewith to the negative terminal of battery. When energized over the above-traced circuit, the control relay R130 operates and the polarized relay R115 operates partially to recomplete, at RA116 and at RA117, the previously mentioned paths for applying negative and positive battery potentials respectively to the conductors C531 and C532 of the line 530 extending to the signal D associated with the branch railway track 90, thereby to cause the signal D to operate to display a caution indication. The operation of the signal D to display a caution indication indicates to a train proceeding along the branch railway track 90 that the track sections 66 and 67 of the main railway track 60 are clear but that the track section 65 of the main railway track 60 is occupied and that the train should proceed into the track section 67 with caution.

Also, upon reoperating, the track relay R105 prepares, at RA108 and at RA109, points in the previously traced original circuit for energizing the winding of the polarized relay R135; and when the control relay R130 reoperates, it prepares, at RA131 and the front contact associated therewith and at RA132 and the front contact associated therewith, further points in the previously traced original circuit for energizing the winding of the polarized relay R135.

When the reference train enters the track section 64, the track relay R195 associated therewith restores, thereby to actuate the associated battery reversing switch S195. Specifically, the battery reversing switch S195 is actuated, thereby to interrupt, at RA196 and the front contact associated therewith and at RA197 and the front contact associated therewith, further points in the previously traced original circuit for energizing the winding of the polarized relay R120 and to prepare, at RA196 and the back contact associated therewith and at RA197 and the back contact associated therewith, an alternative circuit for energizing the winding of the polarized relay R120.

When the reference train clears the track section 65, the track relay R110 reoperates, thereby to interrupt, at RA111 and the back contact associated therewith and at RA112 and the back contact associated therewith, the previously traced alternative circuit for energizing the winding of the polarized relay R115 in series with the winding of the control relay R130 and to complete, at RA111 and the front contact associated therewith and at RA112 and the front contact associated therewith, the previously traced original circuit for energizing the winding of the polarized relay R115 in series with the winding of the control relay R130. When the last-mentioned circuit is completed, the polarized relay R115 completely operates, thereby to complete, at RA118, the previously mentioned path for applying positive battery potential to the conductor C533 of the line 530 extending to the signal D associated with the branch railway track 90

in order to cause the signal D to be operated to display a clear indication. The operation of the signal D to display a clear indication indicates to a train proceeding along the branch railway track 90 that the track sections 65, 66 and 67 of the main railway track 60 are clear.

Also, upon reoperating, the track relay R110 completes, at RA113 and at RA114, the previously mentioned alternative circuit for energizing the winding of the polarized relay R120, this circuit extending from the positive terminal of battery by way of RA197 and the back contact associated therewith, C564, RA113, the winding of R120, RA114, C565 and RA196 and the back contact associated therewith to the negative terminal of battery. When the polarized relay R120 is energized over the above-traced circuit, it re-operates partially, thereby to complete, at RA123 and at RA124, the previously mentioned paths for applying negative and positive battery potentials respectively to the conductors C521 and C522 of the line 520 extending to the signal C associated with the track section 65 of the main railway track 60, thereby to cause the signal C to operate to display a caution indication. The operation of the signal C to display a caution indication indicates to a train proceeding along the main railway track 60 that the track section 65 is clear but that the track section 64 of the main railway track 60 is occupied. Also, upon operating, the polarized relay R120 completes, at RA121 and at RA122, the previously traced original circuit for energizing the winding of the polarized relay R135, thereby to cause the last-mentioned relay to operate fully. Upon operating, the polarized relay R135 interrupts, at RA136 and the back contact associated therewith, the previously traced path for applying positive battery potential to the conductor C551 extending to the order signaling apparatus 201 and recomplete, at RA136 and the front contact associated therewith and at RA137, the previously traced circuit for energizing the winding of the control relay R140, whereupon the last-mentioned relay operates. Upon operating, the control relay R140 interrupts, at RA141, the previously mentioned path for applying positive battery potential to the conductor C550 extending to the order signaling apparatus 201 and interrupts, at RA142, a further point in the previously traced path for applying positive battery potential to the conductor C551 extending to the order signaling apparatus 201.

When the reference train clears the track section 64, the track relay R195 associated therewith reoperates, thereby to actuate the battery reversing switch S195 to its normal position. More particularly, the battery reversing switch S195 is actuated to interrupt, at RA196 and the back contact associated therewith and at RA197 and the back contact associated therewith, the previously traced alternative circuit for energizing the winding of the polarized relay R120 and to complete, at RA196 and the front contact associated therewith and at RA197 and the front contact associated therewith, the previously traced original circuit for energizing the winding of the polarized relay R120, whereupon the last-mentioned relay fully operates. Upon fully operating, the polarized relay R120 recomplete, at RA125, the previously mentioned path for applying positive battery potential to the conductor C523 of the line 520 extending to the signal C associated with the track section 65 of the main railway track 60, thereby to cause the signal C to operate to display a clear indication. The

operation of the signal C to display a clear indication indicates to a train proceeding along the main railway track 60 that the track sections 64 and 65 of the main railway track 60 are clear.

Assuming now that when the dispatcher at the dispatcher station 30 received the coded tone transmitted from the order signaling apparatus 201 over the telephone line 40 incident to the entrance of the reference train into the track section 66 of the main railway track 60, he wishes to operate the signals A and B associated with the track section 64 of the main railway track 60. For example, the dispatcher at the dispatcher station 30 may desire that the reference train proceeding along the main railway track 60 take the branch railway track 80. In order to effect this end, the dispatcher at the dispatcher station 30 operates the corresponding siding impulsive key K310, thereby to cause the apparatus at the dispatcher station 30 to operate, in the previously described manner, and transmit corresponding impulses over the telephone line 40, whereupon each of the selector switches 185, 260, etc., at the various waystations 20, 21, etc., are actuated into corresponding positions. However, only the selector switch 185 is operated to cause the wiper thereof to engage a contact terminating a control conductor as previously noted. Furthermore, at the conclusion of the impulses transmitted over the telephone line 40, the apparatus at the dispatcher station 30 operates to cause ringing current to be projected over the telephone line 40, in the previously described manner, thereby to retain the operated selector switch 185 at the waystation 20 in its operated position, the other selector switches at the other waystations being returned to their normal positions as previously explained.

More specifically, the wiper 186 of the selector switch 185 is operated into engagement with the contacts terminating the control conductor C519, whereupon a series circuit is completed for energizing the winding of the siding relay R145 and the winding of the control relay R170. The last-mentioned circuit extends from the positive terminal of battery by way of the winding of R170, C568, the wiper 186, the associated contact terminating the control conductor C519, C519 and the winding of R145 to the negative terminal of battery. When energized over the above-traced circuit, the siding relay R145 and the control relay R170 operate.

Upon operating, the siding relay R145 interrupts, at RA146 and the back contact associated therewith and at RA147 and the back contact associated therewith, points in the previously traced circuit for energizing the winding of the polarized relay R160 and prepares, at RA146 and the front contact associated therewith and at RA147 and the front contact associated therewith, an alternative circuit for energizing the winding of the polarized relay R160. Further, the siding relay R145 interrupts, at RA149 and the back contact associated therewith, a point in the previously traced holding circuit for energizing the winding of the clear relay R150 and prepares, at RA149 and the front contact associated therewith, a point in a holding circuit, traced hereinafter, for energizing the winding of the siding relay R145. When the holding circuit for energizing the winding of the clear relay R150 is interrupted, the last-mentioned relay immediately restores to complete, at RA154, the previously mentioned holding circuit for energizing the winding of the siding relay R145. The last-

mentioned circuit extends from the positive terminal of battery by way of the resistor 198, RA149 and the front contact associated therewith, RA154, RA158, C519 and the winding of R145 to the negative terminal of battery. Further, the clear relay R150 interrupts, at RA153 and the front contact associated therewith, a further point in the holding circuit for energizing the winding thereof and prepares, at RA153 and the back contact associated therewith, a point in a holding circuit for energizing the winding of the stop relay R155. Finally, the clear relay R150 interrupts, at RA151 and the front contact associated therewith and at RA152 and the front contact associated therewith, further points in the previously traced original circuit for energizing the winding of the polarized relay R160 and completes, at RA151 and the back contact associated therewith and at RA152 and the back contact associated therewith, the previously mentioned alternative circuit for energizing the winding of the polarized relay R160. The last-mentioned circuit extends from the positive terminal of battery by way of RA147 and the front contact associated therewith, RA151 and the back contact associated therewith, C566, the winding of R160, C567, RA152 and the back contact associated therewith, and RA146 and the front contact associated therewith to the negative terminal of battery. As a consequence of the operation of the siding relay R145 and the restoration of the clear relay R150, battery is reversed over the winding of the polarized relay R160, thereby to cause the last-mentioned relay to restore the contact springs RA165, RA166, RA167 and RA168 for a purpose more fully described hereinafter.

Also, upon operating, the siding relay R145 prepares, at RA145, a point in a marking circuit, traced hereinafter, for the answer-back apparatus 203. Upon operating, the control relay R170 completes, at RA171, an obvious path for applying positive battery potential to the conductor C552 extending to the answer-back apparatus 203, thereby to initiate operation of the last-mentioned apparatus. Also, upon operating, the control relay R170 prepares, at RA171, at RA172 and at RA173, additional marking circuits for the answer-back apparatus 203.

When the contact springs RA165 and RA166 of the polarized relay R160 are restored, points are interrupted in the previously traced control circuit for energizing the winding of the polarized relay R175 by way of the line 540 extending to the track relay, not shown, associated with the track section 64 of the main railway track 60, thereby to cause the polarized relay R175 to restore. Upon restoring, the polarized relay R175 interrupts, at RA176, at RA177 and at RA178, the previously mentioned paths for applying negative battery potential to the conductor C501 and positive battery potential to the conductors C502 and C503 of the line 500 extending to the signal A, thereby to cause the signal A to be operated to display a stop indication. It is noted that the restoration of the contact springs RA165 and RA166 of the polarized relay R160 prevents the operation of the polarized relay R175 and consequently the operation of the signal A under the control of the track relay, not shown, associated with the track section 64 of the main railway track 60. When the contact spring RA167 of the polarized relay R160 is restored, a path is completed for applying positive battery potential to the conductor C512 of the line 510,

negative battery potential being applied by way of the previously traced path to the conductor C511 of the line 510. The applications of negative battery potential to the conductor C511 and positive battery potential to the conductor C512 of the line 510 extending to the signal B associated with the track section 64 of the main railway track 60 cause the signal B to be operated to display a take-siding indication. Finally, when the contact spring RA168 of the polarized relay R160 is released, it interrupts, at the front contact associated therewith, a point in a marking circuit for the answer-back apparatus 203 and prepares, at the back contact associated therewith, another marking circuit for the answer-back apparatus 203.

At this time the signals A and B are operated to display stop and take-siding indications, respectively, thereby to indicate to a train proceeding along the main railway track 60 that it is not to proceed further along the main railway track 60 and that it is to take the side railway track 80. Incident to the operation of the signal B from a position displaying a stop indication to a position displaying a take-siding indication, the mechanical switch S180 associated therewith is actuated. More specifically, the wiper 181 of the switch S180 is actuated to disengage the associated contact in order to interrupt a further point in one of the marking circuits for the answer-back apparatus 203; the wiper 182 of the switch S180 is actuated to engage the associated contact, thereby to prepare one of the marking circuits for the answer-back apparatus 203; and the wiper 183 of the switch S180 is actuated to disengage the associated contact, thereby to interrupt one of the marking circuits for the answer-back apparatus 203. Specifically, at this time, only one of the marking circuits for the answer-back apparatus 203 is completed, this marking circuit extending from the negative terminal of battery by way of RA163, RA168 and the back contact associated therewith, C569, RA145, C570, RA172, the wiper 182 of the switch S180, the associated contact terminating the marking conductor C554 and C554 to the answer-back apparatus 203. As previously noted, the application of negative battery potential to the start conductor C552 of the answer-back apparatus 203 initiates operation thereof. The application of marking potential to the marking conductor C554 extending to the answer-back apparatus 203 causes the apparatus 203 to transmit a Morse coded signal by way of the conductor C556 over the line conductors of the line 515 connected by way of the condenser 189 and the choke coils 190 and 191 to the line conductors of the telephone line 40, whereupon the coded signal is transmitted over the telephone line 40 to the dispatcher station 30 as previously noted. Specifically, the answer-back apparatus 203 transmits a unique code signal indicative of the take-siding operated position of the signal B, thereby to verify the actual operated position of the signal B, as determined by the mechanical switch S180 associated therewith, with the desired operated position thereof, as determined by the operation of the take-siding impulsing key K310 and the illumination of the lamp L314 at the dispatcher station 30.

After the dispatcher at the dispatcher station 30 has received the coded signal transmitted from the answer-back apparatus 203 by way of the telephone line 40 to the dispatcher station 30, he may release the answer-back apparatus 203 at

5 the waystation 20 by returning the key K395 at the dispatcher station 30 to its normal position, thereby to effect the release of the answer-back apparatus 203 in a manner similar to the release of the answer-back apparatus 410 at the waystation 21 as previously described.

10 After the reference train has taken the side railway track 80, the dispatcher at the dispatcher station 30 may desire to operate the signal B back to its stop position and render the signal A again under the control of the track relay, not shown, associated with the track section 64 of the main railway track 60. This may be accomplished by actuating the clear impulsing key K315 at the dispatcher station 30, whereupon the apparatus at the dispatcher station 30 operates to cause corresponding impulses to be transmitted over the telephone line 40 and the selector switch 185 at the waystation 20 operates, in a manner similar to that previously described, in order to complete a series circuit for energizing the winding of the clear relay R150 in series with the control relay R170. Incident to the operations of the clear relay R150 and the control relay R170, the signal B is returned to its stop position and the signal A is rendered under the control of the track relay, not shown, associated with the track section 64 of the main railway track 60. The answer-back apparatus 203 then operates to cause a coded signal to be transmitted over the telephone line 40 to the dispatcher station 30, in a manner similar to that previously explained, whereupon the dispatcher at the dispatcher station 30 may verify the actual operated position 20 of the signal B, as determined by the mechanical switch S180 associated therewith, with the desired operation thereof, as determined by the operation of the clear impulse key K315 and the illumination of the lamp L319 at the dispatcher station 30. It is noted that the dispatcher at the dispatcher station 30 may operate both of the signals A and B associated with the track section 64 of the main railway track 60 by operating the stop impulsing key K305 at the dispatcher station 30, whereupon corresponding impulses are transmitted over the telephone line 40, thereby to cause the selector switch 185 to operate and move the wiper 186 thereof into engagement with the associated contact terminating the control conductor C517. When the wiper 186 of the selector switch 185 engages the contact terminating the control conductor C517, a circuit is completed for energizing in series the control relay R170 and the stop relay R155, the last-mentioned circuit extending from the positive terminal of battery by way of the winding of R170, C568, the wiper 186 and associated contact terminating the control conductor C517, C517 and the winding of R155 to the negative terminal of battery. When the above-traced circuit is completed, the control relay R170 and the stop relay R155 operate. Incident to the operations of the control relay R170 and the stop relay R155, operation of the answer-back apparatus 203 is initiated and the polarized relay R160 completely restores, thereby to cause both of the signals A and B associated with the track section 64 of the main railway track 60 to be operated to display stop indications. Incident to the 25 operation of the signal B to display a stop indication, the mechanical switch S180 associated therewith is operated to complete a corresponding marking circuit extending to the answer-back apparatus 203, whereupon the last-mentioned apparatus operates to cause a corresponding coded 30 35 40 45 50 55 60 65 70

signal to be returned over the telephone line 40 to the dispatcher station 30 for the purpose of verification as previously explained.

Although the operation of the railway signaling system has been described in connection with the operation of the apparatus at the dispatcher station 30 and at the waystations 20 and 21, it will be understood that the apparatus disposed at the other waystations may be controlled over the telephone line 40 in a manner similar to that of the apparatus disposed at the waystations 20 and 21. Furthermore, it is contemplated that certain of the waystations will comprise telephone apparatus operative to communicate directly with the dispatcher at the dispatcher station 30 and that ordinary telephone connections will be established between the various waystations having telephone apparatus and the dispatcher station 30. The particular apparatus with which these telephone connections between the dispatcher station 30 and the waystations having telephone apparatus thereat are set up and released forms no part of the present invention and, in the interest of brevity, has been omitted.

While there has been described what it at present considered to be the preferred embodiment of the invention, it will be understood that various modifications may be made therein, and it is intended to cover in the appended claims all such modifications as fall within the true spirit and scope of the invention.

What is claimed is:

1. In a signaling system, an operator position, a signal line associated with said operator position, corresponding impulse devices and signals at said operator position, corresponding control relays, an operating circuit for each of said control relays including the corresponding impulse device, a holding circuit for each of said control relays, an operating circuit for each of said signals, said circuits being so connected and arranged that the holding circuit of one of said control relays and the operating circuit of a corresponding one of said signals are normally completed as determined by the last operated and corresponding one of said impulse devices, means responsive to the operation of another of said impulse devices for completing the operating circuit of the corresponding other of said control relays, means responsive to the operation of said other control relay for interrupting the holding circuit of said one control relay and the operating circuit of said corresponding one signal, means responsive to the operation of said other control relay and the restoration of said one control relay for completing the holding circuit of said other control relay and the operating circuit of said corresponding other signal, an impulse circuit, means responsive to the operation of said other control relay prior to the restoration of said one control relay for operatively associating said impulse circuit with said signal line, and means governed by the operation of said other impulse device for controlling said impulse circuit, whereby impulses individual to said other impulse device are transmitted over said signal line.

2. In a signaling system, an operator position, a signal line associated with said operator position, corresponding impulse devices and signals at said operator position, corresponding control relays, each of said control relays being of the slow-to-release type, an operating circuit for each of said control relays including the corresponding impulse device, a holding circuit for

each of said control relays, an operating circuit for each of said signals, said circuits being so connected and arranged that the holding circuit of one of said control relays and the operating circuit of a corresponding one of said signals are normally completed as determined by the last operated and corresponding one of said impulse devices, means responsive to the operation of another of said impulse devices for completing the operating circuit of the corresponding other of said control relays, means responsive to the operation of said other control relay for interrupting the holding circuit of said one control relay and the operating circuit of said corresponding one signal, means responsive to the operation of said other control relay and the restoration of said one control relay for completing the holding circuit of said other control relay and the operating circuit of said corresponding other signal, an impulse circuit, means controlled by the operation of said other control relay prior to the restoration of said one control relay for operatively associating said impulse circuit with said signal line, means governed by the operation of said other impulse device for controlling said impulse circuit, whereby impulses individual to said other impulse device are transmitted over said signal line, a ring circuit, means controlled after the operation of said other impulse device for operatively associating said ring circuit with said signal line whereby ringing current is transmitted over said signal line, and means at said operator position for disassociating said ring circuit with said signal line.

3. In a railway signaling system, a stretch of railway track, a dispatcher station, a line, a signal device associated with said stretch of railway track and selectively operated to present different signal indications, transmitting equipment at said dispatcher station and selectively operative to transmit different operating signals over said line and to complete a hold circuit including said line, means selectively operative in response to the operating signals transmitted over said line for selectively operating said signal device, first transmitting apparatus remote from said dispatcher station and selectively operative continuously to transmit repeatedly different code signals over said line, means controlled by the operation of said signal device to present a new signal indication for initiating continuous operation of said first transmitting apparatus and for causing said first transmitting apparatus to transmit repeatedly a code signal over said line indicative of said new signal indication, means for maintaining continuous operation of said first transmitting apparatus while said hold circuit is completed, second transmitting apparatus remote from said dispatcher station and operative continuously to transmit repeatedly a code signal over said line indicative of the location of a fixed point along said stretch of railway track, means controlled by the passage of a train over said fixed point along said stretch of railway track for initiating continuous operation of said second transmitting apparatus, receiver means at said dispatcher station for reproducing audibly code signals transmitted over said line, a control device at said dispatcher station operative to interrupt said hold circuit, thereby to arrest continuous operation of said first transmitting apparatus, whereby the code signal transmitted repeatedly by said second transmitting apparatus over said line may be deciphered without interference by the dispatcher at

said dispatcher station in the event of concurrent operations of said first transmitting apparatus and said second transmitting apparatus, and means governable by said transmitting equipment over said line for arresting continuous operation of said second transmitted apparatus.

4. In a railway signaling system, a stretch of railway track, a dispatcher station, a line, a signal device associated with said stretch of railway track and selectively operative to present different signal indications, a control relay, transmitting equipment at said dispatcher station and selectively operative to transmit different operating signals over said line and to complete an operating circuit for said control relay, means responsive to the operation of said control relay for completing a holding circuit therefor and for completing a hold circuit including said line, means selectively operative in response to the operating signals transmitted over said line for selectively operating said signal device, first transmitting apparatus remote from said dispatcher station and selectively operative continuously to transmit repeatedly different code signals over said line, means controlled by the operation of said signal device to present a new signal indication for initiating continuous operation of said first transmitting apparatus and for causing said first transmitting apparatus to transmit repeatedly a code signal over said line indicative of said new signal indication, means for maintaining continuous operation of said first transmitting apparatus while said hold circuit is completed, second transmitting apparatus remote from said dispatcher station and operative continuously to transmit repeatedly a code signal over said line indicative of the location of a fixed point along said stretch of railway track, means controlled by the passage of a train over said fixed point along said stretch of railway track for initiating continuous operation of said second transmitting apparatus, receiver means at said dispatcher station for reproducing audibly code signals transmitted over said line, a control device at said dispatcher station operative to interrupt the holding circuit for said control relay, means responsive to the restoration of said control relay for interrupting said hold circuit, thereby to arrest continuous operation of said first transmitting apparatus, whereby the code signal transmitted repeatedly by said second transmitting apparatus over said line may be deciphered without interference by the dispatcher at said dispatcher station in the event of concurrent operations of said first transmitting apparatus and said second transmitting apparatus, and means governable by said transmitting equipment over said line for arresting continuous operation of said second transmitting apparatus.

5. In a railway signaling system, a stretch of railway track, a dispatcher station, a line, a signal device associated with said stretch of railway track and selectively operative to present different signal indications, transmitting equipment at said dispatcher station and selectively operative to transmit different operating signals over said line and to complete a hold circuit including said line, indicator means at said dispatcher station for presenting visually the last operating signal transmitted by said transmitting equipment over said line, means selectively operative in response to the operating signals transmitted over said line for selectively operating said signal device, first transmitting apparatus remote from said dispatcher station and selectively operative continuously to transmit repeatedly different code signals over said line, means controlled by the operation of said signal device to present a new signal indication for initiating continuous operation of said first transmitting apparatus and for causing said first transmitting apparatus to transmit repeatedly a code signal over said line indicative of said new signal indication, means for maintaining continuous operation of said first transmitting apparatus while said hold circuit is completed, second transmitting apparatus remote from said dispatcher station and operative continuously to transmit repeatedly a code signal over said line indicative of the location of a fixed point along said stretch of railway track, means controlled by the passage of a train over said fixed point along said stretch of railway track for initiating continuous operation of said second transmitting apparatus, receiver means at said dispatcher station for reproducing audibly code signals transmitted over said line, whereby the dispatcher at said dispatcher station may compare the last operating signal presented visually by said indicator means with an audible code signal reproduced repeatedly by said receiver means, a control device at said dispatcher station operative to interrupt said hold circuit, thereby to arrest continuous operation of said first transmitting apparatus, whereby the code signal transmitted repeatedly by said second transmitting apparatus over said line may be deciphered without interference by the dispatcher at said dispatcher station in the event of concurrent operations of said first transmitting apparatus and said second transmitting apparatus, and means governable by said transmitting equipment over said line for arresting continuous operation of said second transmitting apparatus.

SAMUEL G. RABER.
